Robert Genin, Scarsdale, N.Y., assignor to Child Guidance Toys Inc., Bronx, N.Y., a corporation of New York

Filed July 18, 1967, Ser. No. 7,846

Term of patent 14 years

(Cl. D34—15)

FIG. 1 is a perspective view of my design for a toy hand-held movie camera having a transparent casing which exposes the internal gear works of the camera;

FIG. 2 is a front view of the camera showing the lens turret;

FIG. 3 is a rear end view of the camera showing the eye piece; and

FIG. 4 is a top plan view of the camera.

I claim:

The ornamental design for a toy hand-held movie camera, substantially as shown and described.
